DOOR PROP FOR PREVENTING OPENING OF THE DOOR

James W. Nash, 1310 S. Catalina,
Redondo Beach, Calif. 90277

Filed Sept. 30, 1974, Ser. No. 510,597

Term of patent 14 years

Int. Cl. D8—07

U.S. Cl. D8—203

The single figure of the drawing is a perspective view of a door prop embodying my new design.

The surfaces not shown are likewise plain and unornamented.

I claim:

The ornamental design for a door prop for preventing opening of the door, substantially as shown and described.
